UNITED STATES PATENT OFFICE.

GEORGE A. MACKER, OF WESTBOROUGH, MASSACHUSETTS.

DESIGN FOR A SADDLE-SEAT SUPPORT FOR BICYCLES.

SPECIFICATION forming part of Design No. 29,050, dated July 12, 1898.

Application filed June 1, 1897. Serial No. 639,056. Term of patent 3½ years.

To all whom it may concern:

Be it known that I, GEORGE A. MACKER, a citizen of the United States, residing at Westborough, in the county of Worcester and State 5 of Massachusetts, have invented and produced a new and original Design for a Saddle-Seat Support for Bicycles, of which the following is a specification, reference being had to the accompanying drawings, forming part 10 thereof.

Figure 1 is a plan view of a saddle-seat support for bicycles, showing my new design; and Fig. 2 is a view of the bottom or under side of the same.

15 Similar letters refer to similar parts in both figures.

Referring to the drawings, A denotes the cantle, to which the rear portion of the saddle-seat support is attached, and B denotes 20 the front plate, to which the forward end of the saddle-seat support is attached. The leading feature of my new design for a saddle-seat support consists of a flexible strap C, attached at its forward end to the plate B 25 and provided with a series of holes D, said holes extending in a double row throughout nearly the entire length of the flexible strap.

Through the holes D, which are arranged in pairs, the strands E are drawn transversely to said flexible strap C, with their opposite 30 ends attached to the cantle A, each of the strands E being a continuous strip between its attached ends. Interwoven between the strands E are the transverse strands F F, attached at their opposite ends to the outer ends 35 of the cantle.

The essential feature of my design consists of a flexible strap C with a series of holes arranged in pairs throughout its length and a series of strands drawn through said holes 40 transversely to said strap and attached at their ends to the cantle, each of said strands being continuous between its attached ends.

Having described my invention, what I claim as new, and desire to secure by Letters 45 Patent, is—

The design for a saddle-seat support for bicycles, substantially as shown and described.

Dated this 15th day of May, 1897.

GEORGE A. MACKER.
